UNITED STATES PATENT OFFICE.

MALCOLM MACFARLANE, OF LONDON, ENGLAND.

PORTABLE VAPOR-BURNER INCANDESCENT LAMP.

Application filed January 2, 1924. Serial No. 684,067.

To all whom it may concern:

Be it known that I, MALCOLM MACFARLANE, a subject of the King of Great Britain, residing at 151 Farringdon Road, 5 London, E. C. 1, England, have invented certain new and useful Improvements in or Relating to Portable Vapor-Burner Incandescent Lamps, of which the following is a specification.

10 This invention has reference to portable vapor-burner lamps of the kind provided with a body or reservoir for holding paraffin or petroleum under pressure and adapted to produce their own vapor for use with 15 an incandescent mantle or mantles.

The main object of the present invention is to provide a convenient arrangement of such a lamp, which can be used in various 20 positions to give a light either upward or downward without any appreciable difficulty from the shadow of the body or the parts around the burner. For instance whether 25 it be placed on the floor or be hung from the ceiling or from a hook against the wall, the lamp will in all cases throw a useful light clear of the body or reservoir.

Such a lamp is very suitable for almost 30 all purposes for which either ordinary or binnacle lamps are used, but besides giving a superior light, its useful beam or light-zone 35 is not broken up or obstructed by shadows especially from the lamp body or reservoir to any appreciable extent.

According to the invention, the lamp head 35 or burner-proper (comprising the usual vapourizer device, hood or chimney, and the inverted mantle, globe, etc.) is arranged at one side of the lamp body or reservoir which latter is preferably of flat or squat shape 40 and has a suitable handle whereby it can be either suspended from a chain or cord, or hung on a hook or nail against a wall. The said lamp head and body may be approximately on a level and be connected by 45 a short oil tube of the usual kind, so that they are close together thus giving a very compact and neat-looking construction.

The arrangement is such however that 50 when the body is in the normal position, that is to say with its base horizontal, the burner is inclined or tilted at a decided angle, its axis being for instance at about 75° instead of being vertical as in ordinary

arrangements. In this way the inverted mantle is tilted outwardly, and thus throws 55 an effective beam upward past the outer edge of the hood or casing of the vapourizer, when the lamp is standing on the floor for instance.

The globe may be provided with a wire 60 guard consisting for instance simply of two U-shaped wires arranged cross-wise, whereby in effect there are only four wires outside the globe and hence the guard sets up 65 practically no shadow.

Moreover the height of the burner or 70 lamp-head is such that when the body or reservoir is placed on the ground, or standing on its base in the normal way, the globe and its guard will clear the ground, and 75 be side-by-side with the body in a tilted or sloping position, with the globe in its lower part outward or further from the body.

In this position it will for example throw 75 its light in an upward direction from a point near the floor level which is very convenient in garages for instance when working underneath a car.

When however the lamp is used as a 80 wall-lamp and hung on a hook or nail, the lamp head or burner may be exactly vertical, the body being then next the wall but on a slope. This is provided for by suitably sloping the handle or bracket of the lamp, a slot being provided therein in the 85 usual way for a hook or nail-head to engage in. In this position the lamp gives light downwards and sideways and the arrangement may be such that the lower edge 90 of the lamp body is practically clear of the light cone given out from the inverted mantle.

On the other hand the handle or bracket 95 may have a loop or eye for hanging it from a chain or cord, in which case the body or reservoir may be more steeply inclined, the head or globe consequently being tilted somewhat inward towards or slightly underneath it, and being inclined the opposite way to its ordinary inclination. The 100 bottom edge of the said body will then be level with or above the top part of the mantle, and the lamp will give a clear and unobstructed light both sideways and downward.

Hence the lamp can be used in its dif-

ferent positions to give a practically clear and shadowless or uninterrupted illumination either upward, sideways or downward, as desired.

6 The lamp-body or reservoir, which as stated is preferably of squat shape, may in fact be somewhat like a small gas kettle and similarly may have a horizontal handle above it to facilitate carrying. The stem 10 or wire which carries this handle may have a bend or loop such as above referred to for the ready attachment of a chain or other suspender, and its end may be secured in a plate, strip or bracket piece attached 15 to the lamp-body or to the rear edge of its base. This plate or bracket may have a slot in the usual way to facilitate hanging on a hook or nail as mentioned, and be sloped approximately parallel with the axis 20 of the burner-head, so that when it is hung up against a wall, the burner-head itself will be vertical.

In order that the invention may be clearly understood and readily carried into effect 25 reference will now be had by way of example to the accompanying diagrammatic drawings, in which:

Fig. 1 is a side view of one construction of the improved portable lamp,

30 Fig. 2 is a plan thereof.

Figs. 3 and 4 are views to a smaller scale showing respectively the lamp hung as a bracket against a wall, and suspended like an ordinary lamp from a chain or hanger.

35 In these drawings:—

a is the body or reservoir of the portable lamp, *b* is the burner head of the usual type, and *c* is the horizontal handle by which the lamp can be carried about.

40 It will be seen that the body *a* is a squat shape and has a flat bottom so that it will readily stand on a flat surface, such as a work-bench or the floor of a garage for instance. This body is provided with a self-contained air-pump *d* of any suitable kind which screws into the filling hole in the known way. It also has the ordinary vent opening closed by a screw *e* and a connection *f* for the small diameter oil-tube *g*, by 45 which the paraffin or the like passes to the inclined connector tube or hollow arm *h* and from it to the vapourizer inside the burner head *b* carried by the said arm *h*. As the said connector tube *h* is made comparatively short, the burner-head comes close 55 to the side of the body *a*, thus giving the lamp a compact, neat, and well-balanced appearance.

The burner head *b* is of the usual construction for oil-vapor lamps with inverted mantles such as *b*¹. It has a globe *b*² outside of which is a suitable guard such as a pair of U-shaped wire loops *b*³ arranged cross-wise. The four legs of the loops are 60 thus spaced equally around the globe and

protect the same without throwing any shadow. The bottom of the guard *b*³ is practically on a level with the bottom of the lamp, and the mantle is just at the side of the squat body *a* and about level with the 70 top thereof.

The hollow arm or tube *h* may contain the usual filter and is provided with ribs or the like as shown to keep it cool. One end is connected to the casing of the burner head 75 *b* by a union coupling, whilst the other end is provided with a square block or head *h*¹ which is seated in a square bend *z*¹ in an upright flat strip or bracket *i* of iron soldered to the body *a* and extending up to 80 the end of the handle *c*. By reason of the ribs on the tube *h* and the connection of the latter to the bracket *i* instead of the body *a* there is practically no danger of the body 85 becoming heated by transmission from the burner head *b*.

The small oil-tube *g* is looped as shown to give it flexibility and passes through the bracket *i* into the end of the tubular arm *h*, the whole made firm and secure by a fixing 90 nut *i*².

At the rear of the lamp, viz., the side opposite the burner-head *b* is another bracket *k* formed by a wide flat plate arranged at an incline parallel with the burner head. 95 This bracket is provided with a key-hole slot or the like *k*¹ so that the lamp can be hung up by it on a nail or hook as in Fig. 3 against a wall for instance, and will remain steady on account of the width of the bracket, with the burner head practically vertical.

100 The handle *c* is of wood or other non-conducting material and is carried by a stout wire or bent rod *l* secured at its end to the two brackets *i*, *k*. This wire or rod is provided with a bent portion or loop *l*¹ by which it can be hung from a chain or other suspender *l*² as in Fig. 4. The said loop is situated at one end of the handle, so that when the lamp is suspended the body *a* is tilted up out of the way, and the light from the mantle *b*¹ can pass freely sideways and downwards without interference.

110 It will be readily seen that such a lamp has many uses especially for technical, industrial or outdoor purposes. For instance as already explained it will serve to illuminate efficiently the underneath portions of a motor chassis by throwing an upwardly slanting beam when placed (in the Fig. 1 position) directly on the floor, thus greatly facilitating repair work. In the same position it can be placed on the edge of a table 115 or on a shelf or bracket with the burner-head and mantle projecting over the said edge and so giving a light underneath. The positions shown in Figs. 3 and 4 explain 120 themselves after what has been said above, the burner head being vertical in the former,

whilst in the latter it is inclined the opposite way to Fig. 1. It may also be mentioned that the lamp is quite unspillable.

Obviously the above arrangements may be modified in various ways in carrying the invention into effect without departing from the general nature thereof.

I claim:—

1. In a portable oil-vapor burner lamp, 10 the combination of an oil reservoir, a burner head at one side thereof normally inclined in one direction, means for supporting the lamp so that said burner head is vertical, and means for suspending it so that the 15 burner head is inclined in the other direction substantially as described.
2. In a portable vapor-burner lamp, the combination of an oil-reservoir, an inclined

burner head at one side thereof, and an inclined bracket at the opposite side, substantially as described. 20

3. In a portable vapor-burner lamp, the combination of a flat-bottomed oil reservoir, a sloping burner head at one side thereof, a sloping bracket at the opposite side there- 25 of, and a suspender loop arranged above the oil reservoir, substantially as described.

4. In a portable oil-vapor burner lamp, the combination of an oil reservoir, an inclined burner head, a tubular connector-arm 30 having heat-radiating ribs, and a handle to which said connector-arm is secured, substantially as described.

In testimony whereof I affix my signature.

MALCOLM MACFARLANE.
